CLAIM

The ornamental design for a game board and game pieces, as shown and described.

DESCRIPTION

1. Game board and game pieces

Fig. 1.1 is a partially exploded top, right, front perspective view of a game board and game pieces in accordance with the present design;

Fig. 1.2 is a partially exploded top, left, back perspective view thereof;

Fig. 1.3 is a partially exploded bottom, right, front perspective view thereof;

Fig. 1.4 is a front elevation view thereof;

Fig. 1.5 is a back elevation view thereof;

Fig. 1.6 is a left elevation view thereof;

Fig. 1.7 is a right elevation view thereof;

Fig. 1.8 is a top plan view thereof;

Fig. 1.9 is a bottom plan view thereof;

Fig. 1.10 is a top, right, front perspective view of the game board and game pieces; and

Fig. 1.11 is a top, left, back perspective view thereof.

(Continued)

The characteristic features of the design lie in the shape of the game board and 6 game pieces as shown and described.
